UNITED STATES PATENT OFFICE.

WILLIAM E. HIGGINS AND GEORGE S. MANN, OF PORTSMOUTH, NEW HAMPSHIRE.

TRAIN STOP.

1,424,645.

Specification of Letters Patent. Patented Aug. 1, 1922.

Application filed November 19, 1920. Serial No. 425,207.

To all whom it may concern:

Be it known that we, WILLIAM E. HIGGINS and GEORGE S. MANN, citizens of the United States, residing at Portsmouth, in the county of Rockingham and State of New Hampshire, have invented new and useful Improvements in Train Stops, of which the following is a specification.

This invention relates to automatic train control devices and has for an object the provision of means for automatically cutting off the steam and applying the air brakes of a train approaching a signal set against the train.

Another object is the provision of an automatic train control device which is simple in construction, positive in operation and which employs compressed air for operating the throttle valve and the air brakes, the compressed air being released to render the operating mechanism active through the instrumentality of electrically operated means whose circuit will be completed only when the signal is set against an approaching train.

With the above and other objects in view, the invention further includes the following novel features and details of construction, to be hereinafter more fully described, illustrated in the accompanying drawings and pointed out in the appended claims.

In the drawings:—

Figure 1 is a diagrammatic view showing a locomotive in side view with the invention applied thereto, the parts being in position to close the electric circuit for the operation of the invention.

Figure 2 is an enlarged plan view of a portion of a railway track showing the position of the signal operated contact member and illustrating the pilot of an engine about to pass over said member.

Figure 3 is an enlarged fragmentary side elevation showing the mechanism for releasing and operating the throttle lever, parts being broken away to more clearly illustrate the operation of the invention.

Figure 4 is a similar view showing the electrically operated trip and its associated air valves.

Figure 5 is an elevation at right angles to Figure 4.

Figure 6 is an enlarged elevation of the signal operated contact member.

Figure 7 is a section on the line 7—7 of Figure 6.

Figure 8 is a detail front view of the bracket for the signal operated contact member.

Figure 9 is a side view of the same.

Referring to the drawings in detail, wherein like characters of reference denote corresponding parts, the invention which is designed to be used in connection with the usual block signal system, but which may be equally well adapted for use in connection with signals of other character, includes a track mechanism which is designated generally at 10. This mechanism comprises a contact member which includes sections 11 and 12, pivotally connected together as shown at 13. This contact member is secured upon a rock shaft 14 which is mounted in bearings 15 and 16 secured to a tie or other convenient member. The rock shaft 14 has also secured thereto a link 17 which connects the said rock shaft with an extension 18 of the operating rod of a block signal system. Thus, the contact member 12 which normally occupies a depressed position between the rails of the track, will be moved to an elevated position as shown in Figure 1 of the drawings by the operation of the block signal when the latter is set against an approaching train. The contact member is designed to engage a contact member carried by the train and in order to insure a positive engagement between these contact members, the pivot 13 which connects the sections 11 and 12 of the first mentioned contact member is surrounded by a spring 19, which acts to resist the downward movement of the free end of the contact member and in addition compensates for variance of height in the train carried contact member. The outer end of the signal operated contact member is provided with a copper wheel or roller 20 so as to insure free and positive electrical contact.

The signal operated contact member has connected thereto a conductor 21, which forms a portion of an electric circuit which is designed to be completed by the train, as will be hereinafter apparent.

Mounted beneath the pilot 22 of the engine is a contact member 23 which is preferably formed of a copper plate or strip. This plate or strip is set within a groove 24 which receives and acts as a guide to the wheel 20 of the signal operated contact member. Secured to the contact member 23 is a suitably insulated conductor wire 25 which extends

rearward within the engine cab and is connected to a solenoid 26, a conductor 27 connecting the solenoid with one of the locomotive axles so that the current may be grounded through the rails and the circuit completed to actuate the solenoid when the contact 23 engages the signal operated contact. Connected to one of the rails is a conductor G, which, with the conductor 21, leads to a suitable source of current. When the circuit is completed and the solenoid 26 energized, the latter which is of the hammer type and works against gravity will have its core or plunger 28 forced outward. Located in the path of this core or plunger is a trip 29 which is pivotally mounted as shown at 30 upon a bracket 31 secured within the cab. This bracket carries a pin 32 which is located in the path of the trip and acts to limit its movement in one direction.

The trip 29 is provided with a shoulder 33 upon which rests a finger 34 which is carried by an arm 35. This arm is secured upon a shaft 36 mounted in bearings 37 within the cab, three of these arms being preferably mounted upon this shaft, although only one arm is provided with a finger 34.

The arms 35 form a part of a mechanism for operating a number of air valves, the latter being three in number and being indicated at 38, 39 and 40. Each of these air valves has an arm 41 connected to its stem and these arms are connected with the arms 35 by means of a link 42 and as each of the arms 35 are secured to the shaft 36, the valves 38, 39 and 40 will be operated in unison. Connected to one of the arms 35 is one end of a coiled spring 43, the opposite end of this spring being secured to any convenient place within the cab of the engine, such for example, as is illustrated at 44.

The action of the spring 43 is to elevate the arms 41 and open the air valves 38, 39 and 40, the first mentioned valve communicating with the air line to the train so that the brakes will be applied when this valve is opened, while the second mentioned valve communicates with the air line to the engine, and the last mentioned valve 40 controls the air to the sander so that the rails will be sanded simultaneously with the application of the brakes. The valves 38, 39 and 40 are normally held in closed position by the engagement of the finger 34 with the trip 29, but when the circuit is completed through the solenoid 26 and the finger released, the spring 43 will be free to open the valves. The valves may be manually closed after the operation of the brakes by means of a hand lever 45, which in addition to closing the valves, brings the finger 34 into position for engagement with the trip so that the mechanism will be again in position for operation.

In addition to supplying air for the opera-

tion of the brake valves, the valve 38 supplies air to a branch pipe 46 which communicates with a cylinder 47 in which operates a plunger 48. The rod 49 of this plunger extends outward and is connected to a lever 50 which is pivotally mounted as shown at 51 upon the throttle lever 52 which controls the steam supply of the locomotive. The lever 50 is adapted to engage a pin 53 which projects over a dog 54, so that when air is supplied to the cylinder 47, the plunger 48 will be operated to depress the outer end of the lever 50 which will engage the pin 53 so as to depress the dog 54 against the action of a spring 55 and to release the dog from its engagement with teeth 56 of a segment 57 and permit the operation of the throttle lever to close the throttle valve.

In addition, air is supplied to a cylinder 58 by a branch pipe 59 which extends from the pipe 46. Operating within the cylinder 58 is a plunger 61 whose rod 62 is connected to the throttle lever 52 as shown at 63, so that when air is admitted to the cylinder 58, the plunger 61 will be forced inward to operate the throttle lever and cut off the supply of steam. It may be here stated, that in the operation of the invention air first reaches the cylinder 47, so that the dog 54 will be operated to release the throttle lever before the operation of the plunger 61.

The dog 54 which holds the throttle lever 52 in position may be manually disengaged from the segment 57 by means of a hand lever (not shown) which is connected to a link 64, through the medium of a rod 65. This link is pivotally mounted upon the throttle lever as shown at 66 and has a pivotal connection 67 with the dog 54.

Air may be supplied to the valves 38, 39 and 40 through a manifold 68 which is connected to a suitable source of air supply.

The invention is susceptible of various changes in its form, proportions and minor details of construction and the right is here reserved to make such changes as properly fall within the scope of the appended claims.

Having described the invention what is claimed is:—

1. The combination with a signal, of an automatic train stop mechanism including electrically controlled throttle operating and brake operating mechanisms, of a plurality of air controlling valves, including a brake controlling valve and a throttle controlling valve, a rock shaft, spring actuated means connecting the rock shaft with the valves for operating the latter to close the throttle and apply the brakes, a pivotally mounted electrically operated trip and a finger carried by the rock shaft and engaging the trip to hold the valves in closed position until the trip is operated.

2. The combination with a signal, of an

115

110

120

125

automatic train stop mechanism comprising a plurality of air controlling valves, including a brake controlling valve and a throttle controlling valve, an arm extending from the stem of each of the valves, a rock shaft, links connecting the rock shaft with the arms of the valves, spring actuated means connected to the links for operating the valves to close the throttle and apply the brakes, means for holding the valves against operation and automatically operated means for releasing the valves to permit of their operation by the spring.

3. The combination with a signal, of an automatic train stop mechanism comprising a plurality of air controlling valves, including a brake controlling valve and a throttle controlling valve, an arm extend-

ing from the stem of each of the valves, a rock shaft, links connecting the rock shaft with the arms of the valves, spring actuated means connected to the links for operating the valves to close the throttle and apply the brakes, a finger rigid with the rock shaft, a pivotally mounted lever, a shoulder provided upon said lever for engagement with the finger to hold the rock shaft against movement in one direction and automatically operated means engageable with the opposite end of the lever for actuating the latter to release the finger.

In testimony whereof we affix our signatures.

WILLIAM E. HIGGINS.
GEORGE S. MANN.
